UNITED STATES PATENT OFFICE

CHARLOS RADÓ, OF BUDAPEST, HUNGARY

CROWN-SLITTING PLIERS

Application filed July 11, 1927, Serial No. 204,991, and in Hungary August 7, 1926.

With the usual crown slitting pliers hitherto the slitting knife is rigidly secured to the limbs of the pliers so that the knife in slitting describes an arcuate path. This path of the knife is very disadvantageous since upon slitting the solo and pillar crowns only the slitting force is necessary and the lateral bending pressure due to the curved path of the knife greatly enhances the risk of injury 16 of the tooth carrying the crown.

This disadvantage is removed by the use of the crown slitting pliers forming the subject of the invention, as with this the slitting knife by the intermediary of a guide does not 15 describe a curved path but can only move positively up and down in a direction perpendicular to the supporting limb.

Three constructional forms of the invention are shown by way of example in the accompanying drawing, wherein

Fig. 1 is a side elevation of the open pliers,
Fig. 2 is a side elevation of the pliers closed,

Fig. 3 is a cross section of the pliers,

Fig. 4 is a front elevation showing a second embodiment of the invention.

Fig. 5 is a side elevation corresponding to Fig. 4, and

Fig. 6 is a side elevation of a third embodiment of the invention.

With the constructional form according to Figs. 1-3 *a* is the supporting limb, *b* the pressure arm, and *c* the guide rails controlling the movement of the slitting knife *d* in the same direction and standing perpendicular to the supporting limb *a* to which they are secured, the length of said guide rails being equal to the usual length of the crowns. The legs of pliers are indicated at *e*, and the slitting knife *d* is loosely arranged in the free end 25 of the pressure arm *b* and is so drawn along the guide rails *c* that upon movement of the pressure arm it remains quite parallel to the supporting limb *a* and is positively moved up and down in this position. In consequence of 30 this construction the slitting knife does not produce any laterally acting force. The crown can thus be slit off and removed from the tooth carrying it without any danger of fracturing the latter. Moreover the knife 35

does not produce any pressure upon the gums

around the teeth and does not damage them.

With the constructional form according to Figs. 4-6 the end of the supporting limb *a* is trifurcated, which has the advantage that it affords a suitable support for a straight slitting knife or for one curved to the left or right. With the constructional form according to Fig. 5 a guide bar *f* is secured upon and perpendicular to the supporting limb. In the free end of the pressure arm *b* is inserted 40 a member *g* which runs parallel with the supporting limb *a* and in this member is provided a bore through which the bar *f* passes. On the end of the bar *f* is secured an abutment *h*. Pins *i* extend on both sides of the member *g* 45 and project into a downwardly extending groove *j* formed in the arm *b*. The slitting knife *k* which may be straight or bent to the left or right is provided with a pin-like abutment *l* which is inserted in a bore formed in 50 the member *g* and is secured therein by a screw *m*. Upon moving the pressure arm *b*, this moves the member *g* by means of the pin *i* and also the cutting knife inserted therein and guided by the bar *f* in a position parallel 55 to the supporting limb *a*. With the construction according to Fig. 6 the member *g* is provided with a guide extension *o* which passes through an aperture in the supporting limb *a* and is provided at the end with an abutment *h*. Upon movement of the pressure arm in this case the member *g* does not move upon the guide bar but the guide *o* integral therewith slides in the aperture of the supporting limb *a*, whereby the slitting knife is caused 60 to move parallel to the supporting limb.

I claim:

In crown slitting pliers a pressure arm, a stripping knife fixed loosely on said pressure arm, a bar guide onto which said pressure arm is drawn, a supporting branch, said bar guide starting from said supporting branch and connected with the stripping knife, pivots projecting on both sides, and a groove in the pressure arm, said pivots projecting into said 85 groove.

DR. CHARLOS RADÓ.
